UNITED STATES PATENT OFFICE

101,799

DESIGN FOR A COMBINATION SHRINE AND SICKROOM LIGHT

Pearl Stinson, San Francisco, Calif.

Application April 17, 1936, Serial No. 62,182

Term of patent 7 years

To all whom it may concern:

Be it known that I, Pearl Stinson, a citizen of the United States, residing in the city and county of San Francisco and State of California, have invented a new, original, and ornamental Design for a Combination Shrine and Sickroom Light, of which the following is a specification, reference being had to the accompanying drawing, forming part thereof.

Figure 1 is a front view of a combination shrine and sickroom light, showing my new design, and

Figure 2 a top plan view of the same.

I claim:

The ornamental design for a combination shrine and sickroom light, as shown.

PEARL STINSON.
